UNITED STATES PATENT OFFICE.

LARS CHRISTIAN NIELSEN, OF COPENHAGEN, DENMARK.

LUBRICATOR.

SPECIFICATION forming part of Letters Patent No. 295,793, dated March 25, 1884.

Application filed January 26, 1884. (No model.)

To all whom it may concern:

Be it known that I, LARS CHRISTIAN NIELSEN, a subject of the King of Denmark, residing at Copenhagen, in the Kingdom of Denmark, have invented certain new and useful Improvements in Lubricators; and I do declare the following to be a full, clear, and exact description of the invention, such as will enable others skilled in the art to which it applies to make and use the same, reference being had to the accompanying drawings, and to the letters and figures of reference marked thereon, which form a part of this specification, and in which—

15 Figure 1 is a front view of my improved lubricator. Fig. 2 is a longitudinal sectional view of the lower portion of the same. Fig. 3 is a horizontal section on line *x x*, Fig. 2; and Fig. 4 is a cross-section on line *y y*, Figs. 2 and 3. 20 Similar letters of reference indicate corresponding parts in all the figures.

My invention has relation to that class of lubricators adapted to inject oil into portions of machinery, into which the oil can not enter by 25 its own gravity, on account of a counter-pressure, by means of a pump; and it consists in the improved construction and combination of parts of such an injector-lubricator, as herein-after more fully described and claimed.

30 In the accompanying drawings, the letter A indicates the reservoir containing the lubricant, the lower end of which is secured into the top of a rectangular casing, B, having a removable front plate, C, and forming bearings for a shaft, D, which may be revolved by any suitable connection with the moving parts of the engine to which it is attached, the shaft being in this instance provided with a ratchet-wheel, E, prevented from revolving back by a 35 pawl, F, pivoted upon the front plate of the casing and receiving motion from a pawl, G, pivoted upon a lever, H, hinged at its inner end upon the end of the shaft, and receiving a vertical rocking motion from the machinery to which it is connected in any suitable manner. The shaft is provided with an eccentric disk, I, which revolves in a slot, J, in a downwardly-projecting lug, K, of a bifurcated frame, L, which reciprocates, resting upon its under side 40 in the casing; and a piston, M, is secured to one, N, of the upwardly-projecting arms of the bifurcated frame, which piston reciprocates with the frame in a pump, O, sliding in the same plane as the frame and the piston in the casing, bearing with its sides against the front and rear plates of the casing, and with its upper side against the top plate of the casing, and with its under side upon a plate or bearing, P, in the casing. The pump has a lateral perforation, Q, passing from the inner bore of the same out 45 to the rear side plate of the casing, and this perforation or channel may be brought to register with two perforations or channels, R and S, the one R of which is curved upward and connects with the outlet of the lubricant-reservoir, while the other, S, passes out through the rear side of the casing connecting with the machine portion to be lubricated, R being the inlet and S the outlet channel. The other upwardly-projecting arm, T, of the bifurcated 50 frame has a set-screw, U, passing through it, the inner end of which screw is adapted to strike the end of the pump. It will now be seen that as the shaft with its eccentric is revolved, the bifurcated frame will be reciprocated, and by taking the position shown in 55 Figs. 2 and 3 of the pump, and supposing the frame to be moving in the direction of the arrow in the said figures, it will be seen that the piston will be drawn out of the pump, the latter being held from sliding with the piston by the adhesion of the sides of the pump to the sides of the casing, which clamp the pump in such a manner that it only slides by a stronger pressure. As the piston thus is drawn out, it will 60 draw the lubricant from its reservoir into the pump-bore through the inlet-channel, and in traveling out in the direction of the arrow the set-screw upon the other arm of the frame will strike the end of the pump, pushing it out in the 65 direction of the arrow, placing the lateral channel of the pump opposite to the outlet-channel in the rear side of the casing, whereupon the frame will travel back in the direction opposite to the arrow, pushing the piston into the pump, 70 which will now eject the lubricant through the outlet-channel into the parts to be lubricated; whereupon the same motions and the same operation will take place again, and so forth.

The quantity of lubricant ejected by the ap- 75

paratus may be regulated either by adjusting the speed of the shaft and eccentric, or, if a still finer adjustment is desired, by means of the set-screw, which, it will be seen, will regulate 5 the stroke of the pump by being moved farther in or out.

Having thus described my invention, I claim and desire to secure by Letters Patent of the United States—

10. 1. The combination, in a lubricator, of a casing having an inlet and outlet channel opening in the same plane, a pump having a lateral aperture from its bore and reciprocating in a plane so as to bring the aperture to register 15 with the inlet and outlet channel, a piston reciprocating in the pump, and means for reciprocating the piston and pump operated by the machinery to be lubricated, as and for the purpose shown and set forth.
20. 2. The combination, in a lubricator, of a casing having an inlet and an outlet channel opening in the same plane in one side of the casing, a pump sliding inside the casing, having a lateral aperture opening from the inner end of its 25 bore and sliding in a plane so as to bring the aperture to register with the inlet and outlet channel, a reciprocating frame having a piston fitting into the pump secured from one arm, and having a set-screw at its other arm adapt-

ed to strike the end of the pump, and means 30 for reciprocating the frame, as and for the purpose shown and set forth.

3. The combination, in a lubricator, of a reservoir for the lubricant, a casing having an inlet and an outlet channel for the lubricant opening in the same plane in one side of the casing, a pump having a lateral aperture opening from the inner end of its bore and sliding in ways 35 in the casing in a plane so as to bring the aperture to register with the inlet and outlet channel, a frame sliding in the same plane as the pump inside the casing, having two upwardly-projecting arms straddling the ends of the pump and having a downwardly-projecting slotted lug, a piston fitting in the bore of the 40 pump and secured to one arm of the bifurcated frame, a set-screw passing inward through the other arm of the bifurcated frame, and a shaft revolved by the machinery to be lubricated, and having an eccentric disk revolving in the 45 slotted lug of the sliding bifurcated frame, as and for the purpose shown and set forth.

In testimony whereof I affix my signature in presence of two witnesses.

LARS CHRISTIAN NIELSEN.
